[57] CLAIM

The ornamental design for a portable pocket beach bath towel, as shown.

DESCRIPTION

FIG. 1 is a front elevational view of the portable pocket beach bath towel showing my new design;

FIG. 2 is a rear elevational view thereof;

FIG. 3 is an enlarged left side elevational view thereof;

FIG. 4 is an enlarged right side elevational view thereof;

FIG. 5 is an enlarged top plan view thereof; and,

FIG. 6 is an enlarged bottom plan view thereof.

The cloth pattern fragmentarily shown in FIGS. 1-6 is understood to extend throughout the claimed design.
